UNITED STATES PATENT OFFICE.

MAX SACHS, OF NEW YORK, N. Y.

HAND BAG.

Application filed June 17, 1925. Serial No. 37,740.

To all whom it may concern:

Be it known that I, MAX SACHS, a citizen of the United States, and a resident of the city of New York, Far Rockaway, borough 5 of Queens, in the county of Queens and State of New York, have invented a new and Improved Hand Bag, of which the following is a full, clear, and exact description.

This invention relates to ladies' hand bags 10 and has for an object to provide an improved construction wherein a bag of substantially the usual appearance is presented but so formed as to have a secret compartment opening from the bottom of the bag 15 and a secret container in the secret compartment.

Another object of the invention is to provide a lady's hand bag with a pair of frames at the bottom acting to support closure 20 means and also articles not readily carried in the body of the bag.

A still further object of the invention is to provide a hand bag which is formed with a body of substantially the usual construction 25 for ordinary use and a hinged bottom structure formed with means for carrying cosmetics, cigarettes and the like.

In the accompanying drawing—

Figure 1 is a perspective view of a bag 30 disclosing an embodiment of the invention, the bottom being shown open.

Figure 2 is a sectional view on an enlarged scale through Figure 1, the section being taken on line 2—2 thereof.

Figure 3 is an enlarged fragmentary sectional view through Figure 2 on line 3—3.

Figure 4 is a fragmentary perspective view similar to the lower part of Figure 1 but showing a slightly modified construction.

Referring to the accompanying drawing by numerals, 1 indicates the body of the bag which is provided with a frame 2 of any preferred or usual construction connected together by suitable snap knobs 3. The body 1 is formed with an outside covering portion 4 and an inner portion or bag 5. When the fastener 3 is disengaged and the frame 2 opened in the usual manner, the bag 5 will be disclosed, which bag is adapted to be used in the usual manner of hand bags. As illustrated in Figure 2, there is a space 6 between the bag 5 and the cover 4, said space being adapted to accommodate any desired article, as for instance, a secret container 7

stitched at 8 to the cover 4 and to the frame section 9. A draw string 10 is provided at one end of the secret pocket 7 to retain any article placed therein. This pocket or container is particularly designed for receiving 60 large bills or jewelry and when positioned as shown in Figure 2, will be out of the way and also it will be in a position impossible for a thief to steal through the bag 5. Associated with the section 9 is a section 11 forming a complete frame which is hinged together at one point and removably locked together at another point in any suitable manner, as for instance, by the sliding catch 12. This frame is substantially 65 elliptical and presents a flat bottom for the bag more or less ornamental and which does not indicate that the bag can be opened at this point. Preferably, the bag 5 is of less depth than the cover 4 so that there is a 70 space below the bag 5 which is adapted to be filled by suitable articles 13 and 14 which are shown in Figures 1 and 2 as containers for holding cosmetics. Suitable straps or holding members 15 and 16 are provided, 80 which hold these cosmetic containers in place. If preferred, instead of mounting cosmetic containers on the bottom 17, a pocket 18 could be provided for receiving 85 cigarettes 19 or other articles. It will be noted that the pocket 18 or the cosmetic 90 holders do not in any way interfere with the secret pocket or container 7 or do not interfere with placing other articles between the bag 5 and cover 4. By providing the 95 construction set forth, a bag of substantially any desired appearance may be made and yet one or more secret containers or holding members may be provided.

What I claim is:

1. A lady's hand bag, comprising an outside cover, a bag arranged in said cover, a frame connected to the upper edge of said cover and also to the upper edge of said bag so that the interior of the bag will have the 100 appearance of being interior of the cover, a second frame connected with the bottom of said cover, said second frame being formed with a hinged section, means connected with said cover presenting a secret container normally positioned between the bag and cover and extending to said second frame, and means carried by the hinged section of said second frame for supporting articles thereon 105 said hinged section being adapted to be 110

swung to an open position for permitting access to the secret container from the bottom of the bag.

2. A lady's hand bag, comprising a body formed with the usual frame and fastening means therefor and with a bag acting as a lining, a second frame connected to the bottom of said body, said second frame having a hinged portion so that access may be had from the bottom of the body to the interior of the body but exteriorly of said lining, and a flexible container connected to said body near the frame and normally extending into the space exteriorly of said lining.
- 15 3. A hand bag, comprising a body formed with an outside cover, an inner bag or lin-

ing, a frame connected with said bag or lining and said cover so that the bag or lining may act in the usual manner for receiving articles, a second frame connected with the bottom of said cover, said second frame having a hinged section for permitting access to the interior of the body from the bottom thereof, a plurality of strap members acting as means for holding articles on said hinged section, and a flexible bag having means at one end for closing the same and connected at the other end to said cover, said flexible bag being positioned between said lining and said cover.

MAX SACHS.
